IRONING MACHINE

Ward G. Zigler, Chicago, Ill.

Application December 18, 1940, Serial No. 370,595

4 Claims. (Cl. 38—4)

This invention relates to improvements in ironing machines of the roll type disclosed in my prior Patent No. 2,203,936, granted June 11, 1940.

Among the objects of my invention are the following:

To provide means for subjecting the individual ironing chests of the ironing rolls to a hydraulic pressure for forcing the chests at a substantially uniform pressure against the padded surfaces of the rolls;

To provide a system or means for conveying the hydraulic pressure to the respective chests from a common source;

To provide means in the system whereby the chests may be subjected to or relieved of the hydraulic pressure at the will of the operator of the machine;

To provide a compensator for the system whereby the desired volume of hydraulic fluid will be available for all of the chests regardless of the number of chests in the machine;

To provide means for maintaining the desired pressure head on the liquid volume, and to make such means capable of adjustment so that the pressure head may be varied or changed to suit different ironing conditions;

To rockably mount the chests in the machine so that the fabrics passing through the machine need only tilt and not bodily lift the chests to enter between them and their associated rolls;

To provide pressure responsive means in the mountings for the chests at the rolls so that the hydraulic liquid under pressure may act on the chests to move them towards and from the roll;

To provide adjustable spring means for balancing the dead weight of the chests in respect to the roll at which the chests are arranged above said roll;

To provide manifold means for handling the hydraulic medium at the chests whereby all of the chests at each roll may be served from a common source; and

To provide limit switches at the compensator to control the running of the oil pump motor as hereinafter described.

The invention consists further in the features hereinafter described and claimed.

In the accompanying drawings:

Fig. 1 is a side elevational view of my improved ironing machine with a part of the machine frame broken away for the purpose of illustration;

Fig. 2 is a longitudinal sectional view taken through the machine with parts in section and

elevation, respectively, and parts omitted for sake of illustration;

Fig. 3 is a diagrammatic view illustrating the power drive for the machine to be hereinafter more fully described;

Fig. 4 shows the system of my invention for subjecting the individual steam chests of the two ironing rolls to a substantially uniform hydraulic pressure, the figure depicting the parts 10 in elevation and section, respectively; the details of construction in respect to the larger or rear roll and one of its chests being taken on line 4—4 of Fig. 1;

Fig. 5 is a longitudinal sectional view taken 15 through one of the chests of the smaller or front roll on line 5—5 of Fig. 1;

Fig. 6 is a view illustrating details of construction in respect to the chests of the front roll, the view being taken on line 6—6 of Fig. 5;

Fig. 7 is an end view of a detail of construction in respect to a chest mounting to be later described; and

Fig. 8 is a sectional view of the control valve shown in its position opposed to that shown in 25 Fig. 4.

The machine of my invention comprises two ironing rolls 1, 2 mounted on shaft elements 3, 4 supported in substantially horizontal and parallel relation in the machine frame 5. The shaft elements 3, 4 are fixed to the opposite ends of the respective rolls and are journaled in the upright side members of the machine frame, one of said side members being shown at 6 in Fig. 1. It is to be understood that the machine frame has two of these side members, one at each side of the machine, and that the entire frame is bolted or otherwise rigidly secured to the floor or other appropriate base in the room in which the machine is installed.

40 The rolls 1, 2 are power driven, being connected with the drive with which the machine is equipped. This drive is indicated in Fig. 3 and will be later described. In this connection, it may be remarked that the drive on the rolls 1, 2

45 is such that they will be turned in the direction of the arrows in Fig. 2 to carry the linens or other fabrics fed into the machine from the front to the rear end thereof. The rolls 1, 2 are arranged in the machine one in advance of the other with the front roll 1 considerably smaller in diameter than the rear roll 2. In the embodiment shown, the front roll 1 is approximately 24 inches in diameter and the rear roll 2 is approximately 60 inches in diameter. As shown in

50 55 Figs. 1 and 2, the rolls 1, 2 are arranged rela-

tively close together to materially reduce the overall length of the machine and to lessen the length of travel for the fabrics in passing from one roll to the other. The drive on the rolls is synchronized so that both rolls rotate at the same peripheral speed.

The ironing chests for the two rolls are marked 7 and 8, respectively. These chests, in the embodiment shown, are heated by steam. Chests otherwise heated as by gas or electricity may be employed if desired.

The chests 7, 7 for the smaller roll are beneath the underside of said roll to iron one side of the fabrics, while the chests 8, 8 for the larger or rear roll 2 are arranged above the upper side of said roll to iron the other side of the fabrics. In most instances the fabrics are ironed on the wrong side by the front roll and on the right side by the rear roll. For monogrammed pieces the reverse is the practice, the right side being ironed first so that the raised work will not be flattened down by the chests at the rear roll. With the chests disposed as described, the materials are ironed on both sides on one passage through the machine. This saves time, expense and labor as will be apparent. It is pointed out that the machine is essentially designed for ironing the so-called "flat-work," that is, table cloths, napkins, bed sheets, bed spreads and other flat sheet-like articles.

The rolls 1, 2 are padded as customarily used in ironing machines. This implies that each roll 1, 2 is covered on its outer cylindrical surface with a fabric padding which I have marked generally at 9 for the larger roll 2 in Fig. 2. This padding covers the entire outer cylindrical surface of the roll and is composed of the desired number of fabric layers as more clearly depicted in Fig. 3 of my prior patent aforesaid. Also, each roll 1, 2 is made hollow, that is, it has a cylindrical body wall 10 and closing end walls 11, 11 as indicated for the roll 2 in Fig. 4. In addition, each roll 1, 2 is provided with perforations 12 in its cylindrical body wall 10 as indicated for the roll 2 in Fig. 4, and these perforations, as in my prior patent, connect the channels 13 in the outer cylindrical surface of the roll beneath the padding 9 with the hollow interior of the roll. Hence, when a suction effort is exerted on the interior of the roll by a motor driven air exhauster as in my prior patent, the moisture vapors generated at the chests in an ironing operation will be withdrawn from the roll to prevent discomfiture to the operators in the room with the machine and the avoidance of water of condensation to keep the padding dry.

Each roll 1, 2 also contains a coil of pipe through which steam is flowed, as shown in Fig. 3 of my prior patent, to vaporize the moisture liberated in the ironing of the dampened fabrics. Due to the fact that my present invention is an improvement on the machine shown in my prior patent, it is not deemed necessary to duplicate in the present drawings the details just above described. In this connection, I may point out that the shaft elements 3, 4 at one end of each roll is made hollow to provide a passage-way for the leads of the steam coil and for the exhauster connection, respectively. This is shown in my prior patent.

Arranged at the front end of the machine, that is, in front of the smaller roll 1 and suitably supported by the machine frame 5 is a fabric support, which may be in the form of a cross-bar

14. This bar serves to support the linens and other fabrics to be fed into the machine. Endless tapes or string conveyors 15 are disposed between the bar 14 and the roll 1. These tapes 15 run about the feed roller 16 on the inner side of the bar 14 and a suitable wedge-shaped support 17 immediately adjacent the cylindrical surface of the roll 1 as shown in Fig. 1. The roller 16 is connected with the drive of the machine and serves to move the tapes 15 in a direction to carry the linens or other fabrics placed on the tapes into the receiving space between the roll 1 and its arrangement of steam chests 7 as indicated in Fig. 2. The shaft 18 on which the roller 16 is mounted is carried by arms 19 pivoted to the side members 6 of the machine frame at 20 as indicated in Fig. 1. The arrangement includes one or more adjusting screws 21 mounted in the frame of the machine and engaging an extension 22 of the roller mounting to regulate the tension on the tapes 15. The bar 14 is suitably supported from the machine frame.

A sheet metal apron 23 is supported between the rolls 1 and 2 on a rod 24 as shown in Figs. 1 and 2 to guide the materials being ironed from the front roll 1 to the rear roll 2. This apron is preferably made of stainless steel so as to present a smooth and polished surface to the fabrics as they pass thereover. Moreover, stainless steel prevents the apron from tarnishing, the fabrics being ironed by the machine being dampened before being fed into the machine.

Looped around the roll 1 are a plurality of endless tapes or string conveyors 25 arranged in spaced relation along the length of the roll and engaged about the first steam chest 8 of the larger roll 2 as clearly shown in Fig. 2. With this arrangement, the tapes or conveyors 25 are driven by the roll 1 and carry the fabrics from the front roll to the rear roll up and along the outer surface of the apron 23 which extends between the rolls from the last chest of the front roll to the first chest of the rear roll. The apron 23 is slightly curved transversely as shown in Figs. 1 and 2 so that the tapes 25 will be caused to follow the outer surface of the apron as shown and maintain the fabrics in contact therewith. A series of tension devices 26 are rockably supported on a rod 27 journaled in a suitable fixture arrangement 28 carried by the first steam chest 8 to hold the tapes 25 at the desired tautness. These devices form no part of my invention. This fixture also carries a rod support 29 for the loops in the tapes at the steam chest 8 as shown in Fig. 2.

As shown in Fig. 2, the lower end of the apron 23 engages the adjacent chest 7 of the front roll 1 to continue the supporting surface for the fabrics without gaps at said chest. In practice, the lower end of the apron 23 is curved to follow the contour of the front roll and then extends into a recess in the adjacent chest 7 to have an interfitting connection therewith.

65 The fabrics being ironed by the machine are discharged from the rear side of the rear roll 2 onto a plurality of endless tapes or conveyors 30 as shown in Figs. 1 and 2. These tapes or conveyors engage about rollers 31, 32, the former being mounted on a shaft 33 extending between and journaled in the side members 6 of the machine frame at the rear end thereof as shown in Fig. 1. The roller 32 is supported by a pair of arms 34 fixed to a shaft 35 extending across the 70 rear end of the machine and journaled in suit-

able bracket fixtures 36. One or more arms 37 fixed to the shaft 35 may be equipped with weights 38 to maintain the desired tension on the tapes or conveyors 33. The shaft 31 is also connected to the drive of the machine.

This drive in the particular embodiment shown comprises a main shaft 39 extending cross-wise of the machine and journaled at its ends in the side members 6 of said frame. The shaft 39 is located between the rolls 1, 2 at a point below them and carries a beveled gear wheel 40 at one side of the machine. The shaft 41 from the driving motor (not shown) carries a beveled pinion 42 in mesh with the gear 40 to rotate it. Fixed on the shaft 39 within the machine frame 5 are two spur gears which mesh with ring gears 43, 43 on the roll 2. Only one of these spur gears is shown in the drawings at 44 in Fig. 2. The ring gears 43 are fixed to the roll 2 at or adjacent to its shaft elements 4 as indicated in Fig. 4. Also, fixed to the shaft 39 at its end opposite the gear 40 is a gear 45 in mesh with a gear 46 on a countershaft 47. The latter is fixed in the machine frame and carries two sprocket wheels, each indicated at 48 in Fig. 3. A chain 49 connects one of said sprocket wheels with one of two sprockets 50 on a shaft 51 at the front end of the machine. A chain 52 connects the other of the sprockets 50 with a sprocket 53 on the shaft 18 for the roller 16. A chain 54 connects the other sprocket 48 with one of two sprockets 55 on a shaft 56 at the rear end of the machine. The other sprocket 55 is connected by a chain 56a with a sprocket 57 on the shaft 33 for the roller 31 at the rear end of the machine. A chain 58 drives the roll 1 from the shaft 39, there being sprockets 58, 60 on the shafts 39 and 3, respectively. The chain drive 58 drives the first roll 1 and the chains 49 and 54 drive the feed and delivery ribbons 15 and 38, respectively. The larger or rear roll 2 is gear driven as above described.

Referring now to that feature of my present invention in respect to maintaining a constant pressure of the ironing chests 7 and 8 on their respective rolls 1 and 2: This is accomplished by subjecting the chests individually, but simultaneously, to a hydraulic pressure under the control of the operator of the machine through a manually operable control valve in the system which handles the hydraulic medium. This preferably is oil, to avoid variation in pressure and evaporation of the liquid and rusting of the parts which handle and convey it. In this specification, I will describe the hydraulic action first in respect to the chests 8 for the rear roll 2 and then for the chests 7 for the front roll 1. The action is the same for both sets of chests, the only difference being that in respect to the chests 8 the liquid presses the chests downwardly against the roll 2, while for the chests 7 the liquid presses the chests upwardly against the roll 1. The action of the liquid against both sets of chests 7 and 8 is controlled through a single valve in the system.

As illustrated in Fig. 4, each chest 8 is comprised of a hollow body section 61 extending the full length of the roll 2 and providing a steam receiving chamber 62 closed at the ends of the chest by end castings 63, 63. The latter are fixedly secured to the opposite ends of the body section 61 and each terminates in a trunnion 64 in line with the longitudinal axis of the chest. The trunnions 64 are supported for limited rotation in cylindric bearing elements 65, 65 at the

upper ends of piston rods 66, 66 to be presently described. It may be remarked at this point, that with the roll 2 relatively large in diameter the chests 8 may be made relatively narrow so that a 5 relatively large number of these chests may be placed about the upper periphery of the roll 2 with a minimum spacing between the chests to reduce the air gaps between them as in my prior patent. Also, with the chests narrow and the 10 roll 2 large in diameter, the under surfaces of the chests need only conform to a small portion of the curvature of the roll to engage it. Hence, the under surface of each chest is close to a straight line which enables the chest to maintain 15 full contact pressure with the roll 2 cross-wise of the chest as essential to effective ironing. This is also disclosed in my prior patent.

Each bearing element 65 is carried at the upper end of its piston rod 66 in a yoke member 67. As 20 this construction is the same for both rods only one need be described. The yoke 67 spans its bearing element 65 and is connected thereto by bolts 68, 69 arranged in normal relation to the trunnion 64 as shown.

25 The piston rods 66 extend into cylinders 69, 69 carried by the machine frame at the opposite ends of the roll 2 as shown in Fig. 4. The cylinders 69 are set in channel-ways 70 in castings 71, 71 at the upper ends of the side members 6 of the machine frame. The cylinders are clamped in their channel-ways through the packing boxes 72, 72 secured to the castings above the cylinders. The rods 66 extend through the packing assemblies 72 into the cylinders 69 and are equipped at 30 their lower ends with piston elements 73, 73, one on each rod. Each piston 73 slidably engages the inner wall of its cylinder and may be of the type equipped with the so-called "packing leathers" to seal the space in the cylinder above and below the piston against the flow of liquid past the piston.

The system for supplying oil to the cylinders 69 is diagrammed in Fig. 4. As illustrated in this figure, the machine is equipped on each side with 45 a pair of manifolds 74, 75. These elements are long enough to take in the set of cylinders 69 which they respectively serve (see Fig. 1). The manifold 74 is connected with the upper ends of the cylinders which it serves by a series of pipes 76, one for each cylinder. The other manifold 50 75 is similarly connected to the lower ends of the cylinders by pipes 77, one for each cylinder. This is clearly shown in Figs. 1 and 4.

To give the oil the desired pressure head, I 55 provide a motor driven pump and compensator arrangement illustrated in Fig. 4.

The compensator comprises an upright stand pipe or cylinder 78 closed at its lower end by a supporting base member 79 and having a piston 60 or ram element 80 extending into said cylinder through its upper end. The ram has a sliding fit within the cylinder 78 and carries a cross-head 81 at its upper end from which depend rods 82, 82 on the outer side of the cylinder as shown. 65 These rods carry a plate 83 at their lower ends and which plate surrounds the cylinder 78 and provides a support for one or more weights 84, 84. The latter may be applied to the platform 83 over the upper end of the ram 80, but for convenience the weights 84 are divided diametrically for easier application to the plate 83 directly about the rods. The weights 84 are supported in nested relation on the carrying base 83 and by 70 their total weight determine the pressure head on the oil pumped into the cylinder 78 below the

ram. By removing or adding weights, the pressure head on the oil body may be adjusted to that desired. For example, should an eighty pound pressure be desired on the chests the required complement of weights 84 is placed on the carrier plate 83.

The pump referred to is of the motor operated rotary displacement type and is shown at 85 in Fig. 4. The discharge side *a* of the pump 85 is connected by a pipe line 86 with the compensating cylinder 78 through a port 87 in its supporting base 79. The motor for running the pump is indicated at 88. The intake side *b* of the pump 85 is connected with an oil reservoir 89. The pump when operating draws oil from this reservoir and forces it into the compensating cylinder 78 through the pipe line 86 raising the ram 80 until the limit switch 90 (to be presently described) turns off the current to the motor 88 and stops its rotation. At this time there is sufficient volume of oil in the system to exert the desired pressure on the steam chests of the machine.

The discharge side *a* of the pump 85 is connected with the manifolds 74 by a pipe line including a manually operable valve member 91 which in the embodiment shown is of the rotary type having an operating handle 92 and a turning plug body portion 93 containing two separate fluid passages 94, 95 as shown in Fig. 4. The pipe line just above referred to is controlled by the passage 94 and comprises a section 96 connected to the discharge side of the pump 85 at the section 86 and a section 97 connected respectively to the manifolds 74 at the opposite sides of the machine. When the valve 91 is in the position shown in Fig. 4, the upper ends of the cylinders 69 are connected to the compensator 78 and the pressure on the liquid therein as established by the weights 84 is exerted on the upper ends of the pistons 73 to force the chests 8 downwardly against the padded surface of the roll 2 at the same pressure. With the manifolds, all of the chests 8 may be pressed downwardly against the roll 2 simultaneously and at the same pressure. Hence, all of the chests act at a uniform pressure against the roll 2 and effective ironing results.

The liquid in the cylinders 69 below the pistons 73 flows by gravity from said cylinders to the reservoir 89 through the valve 91 by the piping arrangement shown in Fig. 4. This piping comprises sections 98, 99 which respectively connect the manifolds 75 to the valve 91 at its port 95 through a common coupling section 100. The final pipe section 101 connects the valve at said port with the reservoir 89.

To reverse the action above described, that is, to raise the chests 8 from the roll 2 the position of the valve 93 is changed to the position shown in Fig. 8. Now, the passage 94 connects the manifolds 75 to the discharge side of the pump 85, while the passage 95 connects the manifolds 74 to the reservoir 89. This allows oil under pressure to enter the cylinders 69 below the pistons 73 and the oil above the pistons to be forced into the reservoir by the rising pistons. Should the repeated operation of the valve 91 lower the oil column in the cylinder 78 to a dangerously low level, the projection 102 on the weight carrying plate 83 will actuate the lower limit switch 103 and start the motor 88 to replenish the oil supply in the cylinder 78.

The chests 8 are normally urged outwardly from the roll 2 by spring devices, which as shown

in Fig. 4, comprise coiled spring members 104, 104 adjacent to the opposite ends of each chest. These spring members have their inner ends seated in sockets 105 on the associated packing boxes 72 and their outer ends engaged with adjusting screws 106 carried by the end members 63 of the respective chests. With the chests substantially uniform in weight, the weight of the top-most chest forces said chest downwardly towards the roll 2 at a greater pressure than the chests otherwise situated along the curve of the roll. To compensate for this variation of chest weight, the spring members 104 through their screws 106 are adjusted to balance this chest weight so that when the same hydraulic pressure is furnished to all of the chests, the latter regardless of their positions about the curve of the roll will be forced with exactly the same pressure against the padded surface of the roll 2. Hence, the fabrics passing under the chests 8 will receive the same pressure at all of the chests, whether at the top chest or at the chest farther down along the slant or curve of the roll. The chests 7 for the front roll do not need spring devices because the weight of these chests normally urges them away from the roll.

As shown in Fig. 7, a cross-member or plate 107 is secured to each of the trunnions 64 at the end of each chest 8. These cross-members are mounted in slots in the trunnions and have their ends received in recesses 108 in the bearing members 65 in which the trunnions are mounted. The slots 108 are made somewhat wider than the cross-members so that a limited amount of oscillatory movement is permitted for the chests in respect to their mounting in the machine. The slots and the cross-members are radially disposed with respect to the center of the roll 2 and the purpose of this construction is to enable the fabrics to more readily enter beneath the chests because the fabrics need only tilt the chests to pass beneath them and not bodily raise the chests for this purpose.

To supply the chests 8 with steam to heat the chests as required for an ironing operation, each chest is connected with a steam manifold 109 by a conduit 110. These are located on the side of the machine opposite to that shown in Fig. 1. The outlet for the steam from the chests is through a manifold 112 at the opposite side of the machine as shown in Fig. 4. Each chest 8 is connected with this manifold by a conduit 113. These conduits connect with the lower-most points of the chests as indicated in Fig. 4, so as to drain off any water of condensation. The steam supply pipe for the manifold 109 is similar to the pipe 114 (Fig. 1) which is the return pipe connected to the manifold 112. For a rapid distribution of the steam to a chest, the conduit 110 may have inlets distributed along the length of the chest.

Turning now to the chests 7 for the smaller or front roll 1: These chests are constructed and mounted alike and only one need be described. As shown in Fig. 5, the chest 7 is hollow providing a steam chamber 115 closed at the opposite ends of the chest by castings 116, 116 each providing a trunnion element 117 mounted in a bearing element 118 having a cylindric bore to receive the associated trunnion. The chests 7 also have a limited rocking movement axially, the cross-members 119 fixed to the trunnions 117, extending into slightly widened slots 120 in the bearing elements 118 as for the chests 8. The cross-members 119 and their slots 120 are ar-

ranged in substantially normal relation to the radius of the roll 1 as shown in broken lines in Fig. 1.

The chests 7 also have their hydraulic piston and cylinder assemblies as shown in Fig. 5. The piston elements 121 slide in cylinders 122 and have piston rods 123 connected with the respective bearing elements 118, by lug and pin connections 124, 125, respectively. The cross-members 119 and their wider slots 120 permit the chests 10 to rock axially when desired.

The cylinders 122 are supported by the side members 6 of the machine frame 5 below the roll 1 as shown in Fig. 5. The cylinders 122 are secured to the side members 6 of the machine frame 15 in the positions required by bolts 126 inserted through webs 127 cast integral with the sides of the cylinders, as shown in Fig. 5. Each cylinder 122 is connected above and below its piston 121 with the oil supplying system heretofore described 20 by conduits 128, 129. The conduit 128 connects its cylinder 122 with a manifold pipe 130 and the conduit 129 connects the cylinder with a manifold 131. The pipe 130 is connected with the manifold 74, while the pipe 131 is connected with the manifold 75. This is indicated in Fig. 1. Hence, when the valve 91 is turned to supply liquid under pressure to the upper ends of the cylinders 68, liquid under pressure is supplied at the same time to the lower ends of the cylinders 122. This causes the pistons 121 to be forced upwardly or towards the roll 1 to press the chests 7 against the padded surface of said roll while the chests 8 are forced downwardly against the roll 2. On the other hand, when the valve 91 is turned to supply liquid 30 under pressure to the lower ends of the cylinders 69, the same liquid under pressure is supplied to the upper ends of the cylinders 122.

The chests 7 are connected to the steam manifold by pipes or conduits 132 and to the return by 40 conduits 133.

The mountings for the ends of the chests 7 in the machine frame comprise slide-ways 134 radially disposed in respect to the roll 1 and formed between spaced side plates 135, 135 secured or otherwise rigidly fixed to the machine frame as shown in Fig. 6. The bearing element 118 fits between these plates in the slide-way and has flat outside surfaces to conform to the same as indicated in Fig. 6. Hence, the pistons 121 when actuated by the pressure fluid may move the chests 7 50 towards and from the roll 1 as previously described.

To provide a more or less continuity of the fabric supporting surfaces between the lower chests 7, the center chest is provided along each side with spaced lugs 136 which interfit in recesses 137 between similar lugs 138 on the side chests as shown in Fig. 6. The purpose of this is to avoid gaps between the chests 7 for the materials to catch in or pass through. This is shown in Fig. 6. The same arrangement may be provided for the chests 8, 8.

The statements of operation employed throughout the foregoing description of the structure of the machine and its parts are believed to present a full description of the operation and use of the machine. Summarized briefly, however, the operation of the machine is as follows:

The machine is set in operation by turning on the power to the main shaft 41. This through the gear and chain drive as heretofore described rotates the ironing rolls 1, 2 at the same peripheral speed and in the direction of the arrows shown in Fig. 2. Also, the tape conveyors 15 and 30, re-

75 spectively at the front and rear ends of the machine are driven towards and from the rolls 1, 2 as shown by the arrows in Fig. 2. Before the fabrics to be ironed are fed into the machine, the desired ironing pressure for the chests 7, 8 at the respective rolls 1, 2 is established by the hydraulic system depicted in Fig. 4. The motor 88 is set in operation to supply the compensating cylinder 78 with oil from the reservoir 89. The necessary number of weights 84 are placed on the plate 83 to establish the desired pressure head on the liquid column for the chests 7 and 8. As heretofore indicated, if an eighty pound pressure is desired on the chests 7 and 8, the necessary complement of weights 84 is placed on the ram 80. The cylinder 78 is pumped up until the contact 102 on the ram 80 trips the limit switch 90 to turn off the current to the motor 88 stopping its rotation.

The machine is now ready for an ironing operation. The operator now turns the valve 93 by the handle 92 and subjects the chests 7, 8 to the predetermined hydraulic pressure from the cylinder 78. The damped fabrics are now fed into the machine at its receiving or front end unto the tapes or conveyors 15. The latter carry the fabrics into the receiving space between the front roll 1 and the support 17. The leading edges of the fabrics are picked up by the rotating roll 1 and are carried around over the chests 7. As the latter are heated, the fabrics are ironed on one side, that is, the side or surface in contact with the chests. If the under side of the fabrics are to be ironed first, the fabrics are fed into the machine in a manner to accomplish that result.

From the roll 1, the fabrics are conveyed by the tapes 25 up and over the apron 23 to the larger or rear roll 2. The fabrics pass into the receiving space between this roll and its first chest 8 and the fabrics are then carried by the roll 2 under all of the chests 8. Steam has been turned on to these chests and the latter are heated to iron the side of the fabric in contact therewith. It is to be understood that the hydraulic pressure presses and holds the chests 8 against the roll 2 at the same pressure at which the chests 7 are pressed against the roll 1. With the rear roll 2 considerably larger in diameter than the front roll 1, the length of the travel of the fabrics over the rear roll is longer than the length of travel of the fabrics under the front roll, the time interval being such that the fabrics are completely ironed on both sides in one passage through the machine. Hence, the ironing is complete when the fabrics reach the air stripper 139 and are carried from the machine by the discharge conveyors 30. Also, the fabrics at this time are sufficiently dry to leave the machine as completely ironed and finished on both sides. The tapes 30 preferably carry the finished fabrics to a receiving table or equivalent element with which the machine is usually provided at its rear end.

Any leakage or wastage of the oil in the hydraulic system which may occur in the working of the machine over given periods of time will be replaced by the limit switch 103 turning on the motor 88 to replenish the oil supply to the cylinder 78, when the ram 80 descends far enough to actuate said switch. The operator may at any time relieve the pressure of the chests 7, 8 on the rolls 1, 2 by turning the valve 93 in the appropriate direction. For example, for the chests 7, the hydraulic pressure is changed from the lower to the upper ends of the pistons 121 to relieve the roll 1 of chest pressure. Changing the hydraulic pressure from the upper to the lower ends of the

piston 13 relieves the roll 2 of chest pressure. In the actions just mentioned the pistons 121 are moved downwardly to carry the chests 7 away from the roll 1, while the pistons 73 are moved upwardly to raise or lift the chests 8 from the roll 2. Turning the valve 93 in the reverse direction causes the hydraulic medium to press the chests 7, 8 simultaneously against their respective rolls and at a uniform and constant pressure. The two positions of the valve 93 are shown in Figs. 4 and 8, respectively. The first position produces chest pressure, while the other position relieves chest pressure.

The hydraulic pressure may be changed to suit different ironing conditions by adding weights 84 to the ram 80 or removing weights. The hydraulic system is under the control of the operator at the valve 93, and hence the pressure on the steam chests may be readily and easily applied or relieved at the will of the operator.

The structure shown and described provides an efficient and practical roll ironer for flat work. The pressure system enables a pressure to be placed on the chests of both rolls simultaneously and uniformly throughout the machine. This provides for efficient ironing because the same pressure can be maintained at both rolls 1, 2 to give the desired gloss and finish to the materials passing through the machine. The finished articles are stripped from the rear roll on its discharge side by a stripper element 139 as shown in Fig. 2. This stripper may be of the air jet discharge type to both strip the fabrics from the roll and to cool the fabrics as they leave the roll. Other and further objects of my invention will be apparent to those skilled in the art to which my invention pertains.

The limit switches 90 and 103 are mounted on an upright standard or post 140 forming a part of the compensator assembly. These switches are of the conventional circuit making and breaking type, the lead wires which connect the switches in the circuit for the oil pump motor being marked 141, 142, respectively in Fig. 4.

It will be noted that the conveyor 15 at the front end of the machine terminates at the roll 1 above the first chest 7. This allows the incoming edges of the fabrics to be ironed out by the roll 1 before being drawn into the space between the roll and the chests 7. The advantage of this is to avoid ironing the fabrics with turned over or folded edges.

The details of construction and arrangement of parts shown and described may be variously changed and modified without departing from the spirit and scope of my invention, except as pointed out in the annexed claims.

I claim as my invention:

1. In an ironing machine, in combination, a supporting frame, a padded ironing roll journaled in said frame, means for rotating said roll, a plurality of independently movable ironing elements disposed above the roll and in circumferentially spaced relation about the curvature of the same, means for holding the elements in operative relation to the padded surface of the roll, means for subjecting the ironing elements to a hydraulic fluid under pressure for forcing the elements simultaneously into pressing engagement with the roll, spring devices providing a yieldable support for each ironing element at the roll, and means for adjusting the tensions of the springs to balance the dead weight of the ironing elements at the various locations of the elements along the curve of the roll.

2. In an ironing machine, in combination, a supporting frame, a pair of padded ironing rolls journaled in said frame, one in advance of the other, with the front roll considerably smaller in diameter than the rear roll, ironing elements for said rolls, the ironing elements for the front roll being arranged beneath said roll and the ironing elements for the rear roll being arranged above said roll, means for holding the elements in operative relation to the padded surfaces of their respective rolls, means for rotating the rolls by the machine to pass from the underside of the front roll to the underside of the rear roll, tape conveyors extending between the rolls across the space between them and driven by the drive for the rolls, and an apron member mounted in the space between the rolls and extending in an upwardly inclined direction from the front to the rear roll for guiding the fabrics in their passage from one roll to the other, said apron being curved transversely to cause the tapes to follow the same.

3. The ironing machine combination of claim 2 characterized by the fact that the apron and the chest of the front roll next adjacent to the apron have an interfitting connection to continue the fabric support from said chest to the apron.

4. In an ironing machine, in combination, a supporting frame, a padded ironing roll journaled in said frame, means for rotating the roll, an ironing element for the roll, a mounting for holding the ironing element in operative relation to the padded surface of said roll, cooperating trunnions and bearing elements in said mounting at the opposite ends of the element, and interfitting projections and slots on the trunnions and in the bearing elements, respectively, for limiting the rocking movement of the element.

WARD G. ZIGLER.
